UNITED STATES PATENT OFFICE.

AARON PETERSON, OF CHICAGO, ILLINOIS.

RENEWABLE SAFETY-FUSE.

1,375,171.

Specification of Letters Patent. Patented Apr. 19, 1921.

Application filed June 20, 1919. Serial No. 305,467.

To all whom it may concern:

Be it known that I, AARON PETERSON, a citizen of the United States, residing at Chicago, in the county of Cook and State of Illinois, have invented certain new and useful Improvements in Renewable Safety-Fuses, of which the following is a specification.

This invention relates to new and useful improvements in fuses of the cartridge type.

One of the principal objects of the invention is to provide a cartridge fuse in which the knife blade terminals are detachably connected with the respective ends of the casing in a novel manner to permit said casing and blades having relative longitudinal movements, whereby said blades, with connected faces, may be readily inserted within the casing, and the blades firmly clamped thereto.

Another object of my invention is to provide a cartridge fuse of the character above described in which the connecting means for the terminal blades are of such construction as to prevent relative oscillation of the blades when the same are being connected, or even disconnected, from the casing.

Another object of the invention is to provide a knife blade terminal from a blank of metal, and to provide a fixed collar thereto in a novel manner.

A further object of the invention is to provide a terminal blade with a 2-part and detachable interlocking collar which operates with the fixed collar on the blade to limit the inward movement of said blade relative to the casing.

These and other objects will in part be obvious, and will be hereinafter more fully disclosed.

In the drawings,

Figure 1 is a longitudinal sectional view through my improved cartridge fuse.

Fig. 2 is a detail sectional view showing one end of the casing and the ferrule before the same have been connected.

Fig. 3 is a transverse sectional view taken on the line 3—3 of Fig. 1.

Fig. 4 is a similar view, but taken on the line 4—4 of Fig. 1.

Fig. 5 is a detail sectional view taken on the line 5—5 of Fig. 3, and at right angles to the sectional view of Fig. 1.

Fig. 6 is a detail sectional view of a modi-

fied form of ferrule applied to one end of 55 the casing.

Fig. 7 is a plan view of a flat form of fuse; and

Fig. 8 is a perspective view of one of the knife blade terminals. 60

In the drawings, 5 represents an open-ended tubular casing preferably formed of fiber. Threaded ferrules 6—6 are respectively pressed on to the end portions of the casing. Each ferrule is provided with an 65 inwardly extending annular rib 7 adjacent the inner end thereof, which engages a corresponding groove 8 in the outer face of the casing. The outer end of the ferrule is provided with an inwardly extending flange 9, 70 having a centrally disposed opening 10 of the same diameter as the internal diameter of the casing. The ferrule is normally flared, as shown in Fig. 2, and after the end of the casing has been inserted against the 75 flange 9, the wall of the ferrule is pressed tightly around the casing, causing the rib 7 to fit the groove 8 and thereby permanently interlock and thereby secure said ferrule and casing against relative movements. 80 The outer end of the ferrule is provided with an exterior thread 11, the thread on one ferrule being right-handed, and the thread on the other ferrule being left-handed.

Each knife blade terminal 12 is centrally 85 provided along its side edges with cut-out portions 13—13, each forming resultant upper and lower shoulders 14 and 15. These cut-out portions 13 form a resultant reduced portion or web 16, and the opposite faces of 90 this web 16 are respectively formed with grooves 17—17, which are disposed adjacent and merge with the shoulders 15—15. The grooves 17—17, of course, extend transverse to the longitudinal axis of the terminal. 95 Each terminal is provided adjacent one end with a threaded opening 18, and a clamp screw 19 is threaded into said opening for clamping one end of the fuse 20 to said terminal.

The fuse in Fig. 1 is a wire fuse and is provided with one or more weakened portions 21. In this case, the weakened portions 21 are created by flattening the wire and there are two of these portions arranged 105 adjacent their respective terminals. In Fig. 7, I have shown a flat form of fuse 20'. The ends of the fuse 22 are provided with at-

taching forks 23—23, and the body of the fuse is cut-out, as at 24—24 to form spaced reduced portions 21'—21'.

Rigidly secured to each terminal 12 is a 5 collar, which, in this instance, is made from two disks 26 and 27. Each disk is provided with a centrally disposed rectangular opening 28 for receiving the web 16 of the terminal. Each disk is slit as at 29. Each 10 disk, which is made of copper, is normally formed with a slot at the point of the slit, said slot being sufficiently wide to permit the disk to be slid on to the web 16 along the groove 17 thereof. After the web has 15 thus been inserted the said slots are closed by pressing the parts of the disk together. After the two disks have been thus positioned, they are crushed so as to bring the slotted ends in close relation and thereby 20 form a tight interlocking connection with the web 16. The diameter of these disks is slightly less than the interior diameter of the casing.

A removable collar is also associated with 25 each terminal 12. This removable collar is indicated as a whole by the numeral 30, and includes two sections 31 and 32 respectively. The sections are alike and are conjointly formed with an opening 33 which snugly 30 fits the web 16. The collar is formed into two sections by being separated along the lines 34—34. Formed in each section and on opposite sides of said web are openings 35—35 for receiving pins 36—36 permanently secured to the fixed collar. At the 35 ends of the slot 33 the outer surfaces of the sections 31 and 32 are each inclined toward the web 16 to permit the sections to be slipped under the shoulders 14 and then 40 engage with the pins 36. It will thus be seen that I have provided a two-part collar which has interlocking engagement with the terminal through the medium of the fixed collar.

45 In operation, after the fuse wire 20 has been connected to the terminals by the screws 19, the entirety is slipped through the open-ended tubular casing, and the two-part collars 30 are then detachably connected 50 with the respective terminals. These collars 30 have a diameter greater than the interior diameter of the casing, and consequently bear against the outer ends of the ferrules. The end caps are then slipped over the projecting ends of the terminals, and both end caps and terminals are held against rotary movement while the casing is simultaneously screwed into both end caps by reason of the right and left hand threads thereof. When 55 it is desired to insert a new fuse wire, or to inspect the same, the reverse operation, as above described, is performed. In both cases, however, the end caps and terminals

are held against rotary movement while the casing is either connected or disconnected 65 from the end caps.

In the modification shown in Fig. 6, the casing 5 is provided with a ferrule 41, which is inserted within the end of the casing and then expanded so that the outwardly extending rib 42 will engage a corresponding groove formed in the inner face of the casing. The ferrule is exteriorly threaded as at 43, for the same purpose as previously described. 75

The casing is centrally provided with a removable plug 44 for the outlet of any gas which may be generated within the casing, which plug will be blown out by the excessive pressure of the accumulated gases, 80 thus preventing the casing being destroyed or damaged.

Having thus described my invention, what I claim is:

1. The combination with a flat terminal 85 blade having opposed recesses merging with its side edges and forming a resultant web, and a collar fixedly secured to said web and having a slit extending from the web to the periphery thereof. 90

2. The combination of a terminal blade having opposed recesses merging with its side edges and forming a resultant web, and a collar fixedly secured to said web, said collar being formed from two superimposed 95 disks, pins uniting said disks, each disk having an opening to receive the web and having a slit extending from the opening to the periphery thereof to receive said web.

3. The combination of a terminal blade 100 having opposed recesses merging with its side edges and forming a resultant web, a collar fixedly secured to said web, and a removable collar of a greater diameter than the fixed collar having interlocking engagement with said web and fixed collar. 105

4. The combination of an open ended tubular casing, spaced terminal blades extended into the open ends of said casing, a fuse connecting said blades, each of said 110 blades having opposed recesses merging with its side edges and forming a resultant web, a collar fixedly secured to said web and having a slit extending from the web to the periphery of said collar, a removable collar 115 of greater diameter than the fixed collar having interlocking engagement with each of said webs and each of the fixed collars, and detachable means respectively coöperating with said blades and casing to lock 120 said blades against longitudinal movement relative to the casing.

In testimony whereof, I hereunto subscribe my name this 17th day of June, A. D., 1919.

AARON PETERSON.
